UNITED STATES PATENT OFFICE.

WILLIAM ROWLEY BRENNAN, OF HAWTHORN, NEAR MELBOURNE, VICTORIA,
AUSTRALIA.

LATCH.

1,192,271.

Specification of Letters Patent. Patented July 25, 1916.

Application filed January 3, 1916. Serial No. 69,859.

To all whom it may concern:

Be it known that I, WILLIAM ROWLEY BRENNAN, a subject of the King of Great Britain, residing at Hawthorn, near Melbourne, Victoria, Australia, have invented certain new and useful Improvements in Latches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to latches for the doors of motor vehicles, carriages and the like, and has for its object to provide a simple, durable and readily assembled latch, that may be sold at a cost of a few cents. To this end it is necessary that all of the parts be assembled with as few rivets or screws as possible, in order to decrease the assembling costs. With this end in view I have designed such a latch, which can be assembled by providing a single rivet in the latch itself, and a single rivet in the strike plate, and which will fulfil all the requirements of an antirattling automobile latch.

In order that my invention may be readily understood, I will refer to the accompanying drawings which illustrate a practicable embodiment of the invention, and in which like parts are similarly designated.

Figure 1 is a side elevation of the latch; Fig. 2 is a section on line 2-2 of Fig. 1, showing the strike-plate in operative relation to the latch; Fig. 3 is a section on the line 3-3 on Fig. 1; Fig. 4 is a plan view of the latch and strike plate corresponding to the positions shown in Fig. 2; Fig. 5 is a perspective view of a spring-urged pawl or lever for holding the bolt.

The frame plate is made from a single piece of sheet metal, die-formed and punched to comprise a side wall 1, a top member 2, a front member 3, and a bottom member or lug 4. The top is provided with a slot 5 extending from its rear edge arranged for the reception of the operating rod 6, which is preferably made from polygonal stock, preferably rectangular in section, as shown. The lower end of the actuating rod passes through the lug 4, which is

provided with a perforation corresponding in shape to the cross-section of the rod, and at a slight distance from the wall 1, as will be hereinafter explained. The rod 6 is squeezed, preferably in a cold state, to form a recess or transverse slot at 7, for the latch tail 9, and in so doing the metal is displaced laterally. A spring 8 is placed on the rod 6 between the lug 4 and the displaced metal at 7. The rod 6 actuates the latch member. The tail 9 of the latch member 10 enters the transverse recess or slot in the rod 6 at 7. The latch, which is also die-formed of sheet metal, has a perforation 11 near the tail 9 which takes over a boss 12 formed by perforating or punching up the side wall 1. The head 13 of the latch is made heavier and V-shaped in section by doubling the metal from which the latch head is made upon itself, as more clearly shown in Figs. 1 and 2.

The head of the latch moves through a rectangular or oblong slot 14 in the front plate 3. The tail 9 of the latch, in order to be securely seated in the squeezed transverse recess 7 in the rod 6, is bent slightly toward said rod, as indicated at 9a. This also enables the rod 6 to be located a sufficient distance from the plate 1 to enable a coil spring to be placed on rod 6, as shown.

When the rod 6 is depressed, against the action of the spring 8 the latch 13 is raised to the dotted line position shown in Fig. 1, in which position it is held by a pawl 15, also formed of a single piece of sheet metal. The nose of this pawl is formed at 16 so as to lie flat against the plate 1, and is beveled at 17 on its end, Fig. 1, to lie parallel with the underface of the latch head 13, when in raised position, although, if desired, this bevel may be omitted and the parts allowed to wear into this shape.

The pawl 15 is pivoted at 18 on a rivet or the like, which passes through the front plate 3, and is the only rivet in the latch proper. The tail of the pawl 15 is broadened at 19 to act as an abutment or striking surface, and this face is extended at right angles thereto into a lug 20 on which is placed a coil spring 21, the under edge of the surface 19 forming an abutment for one end of the spring 21 and the plate 1 forming an abutment for the other end of said spring. The lug 20 acts as a retainer for spring 21, and is sufficiently long to prevent the nose of

the pawl from moving out at an angle to the edge of the front plate when the end of this lug 20 strikes the plate 1 that acts as a positive stop for the pawl 15.

5. The strike-plate 22, Fig. 2, is provided with a V-shaped hole 23, one side of which, 23^a is substantially vertical, or parallel to the edge of the plate. This plate has a portion 24 at right angles, bent over on itself so 10 as to form a yoke or pocket 25 for the reception of the rubber buffer 26 held in place by a rivet, screw, or the like, 27.

In assembling the latch the spring 21 is placed on the pawl lug 20 and the rivet 18 is 15 inserted and riveted in place. The latch 10 is then laid on the boss 12. The spring 8 is now placed over the lower end of rod 6, and the lower end of this rod is passed through the perforation in the lug 4 at an incline, as 20 indicated by the line A, and is then rocked into the slot 5, while the transverse slot at 7 takes over the latch tail 9. The metal on the outer edge of the slot 5 is then tapped with a hammer and slightly deformed or bent in- 25 ward, as shown at B, Fig. 4. This completes the assembling of the latch by means of a single rivet, screw or the like, 18. The rubber buffer 26 is now slipped over into the yoke or pocket 25, and the rivet, screw, or 30 the like 27, is inserted. The parts in plan view then assume the position shown in Fig. 4 when placed on an automobile door or the like.

When the door to which the latch is 35 secured is slammed shut, it moves in the direction of the arrow Fig. 4 against the rubber buffer 26 in the strike-plate 22, the broadened tail 19 of pawl 15 engages this buffer, and the tail of the pawl is moved toward the 40 plate 1 until lug 20 strikes said plate 1, at about which time the nose of the pawl has been withdrawn from under the latch head 13, whereupon spring 8 urges rod 6 and the latch tail 9 upward, causing the latch head 45 13 to move down in the rectangular slot 14 of the front plate 3 and in the slot 23 of the strike-plate. Inasmuch as at the moment the pawl releases the latch head 13 by the slamming of the door, the buffer 26 yields, 50 and allows the door to move into closing position and slightly past it, a fraction of an inch, so that the hole 23 in the strike-plate must have an inclined edge 23^b. This inclined edge is so arranged and at such an 55 incline, that should the buffer 26 wear out or drop out from any cause, the latch would still close. The buffer, however, exerts a pressure against the pawl tail 19, and urges the straight side of the bolt-head 13 against the vertical edge 23^a of the strike-plate slot, and thus prevents the door from rattling. 60 In lieu of the rubber buffer I can use a heavier spring 21 for the pawl.

I claim—

65 1. In a latch, a pivoted latching member,

a spring-urged actuating rod, a spring-urged pawl to hold said member in unlatching position and a strike-plate having a slot for said member and an abutment to strike the pawl and release said member. 70

2. In a latch, a pivoted latching member having a V-shaped head, a spring-urged pawl to hold said member in unlatching position, a strike plate having a buffer for engaging and releasing said pawl, and a 75 V-shaped slot having its inclined side adjacent said buffer.

3. In a latch, a spring-urged, pivoted, sheet-metal latching member having a head in which the metal is bent over upon itself to 80 substantially V-shape in section, a pivoted, spring-urged pawl whose nose engages under said head, and a strike-plate having a yielding buffer arranged to strike the tail of said pawl to release said member, and a 85 V-shaped slot having one side vertical and the inclined side adjacent the buffer.

4. In a latch, a sheet metal frame plate having a front member provided with a slot, a top member provided with a slot extending 90 from its rear edge for an actuating rod and a bottom member having a perforation in line with the latter slot for said rod.

5. In a latch, a sheet metal frame plate having a front member provided with a slot, 95 a top member provided with a slot extending from its rear edge for an actuating rod, a bottom member having a perforation in line with the latter slot for said rod, and a boss punched from the body plate for a 100 latch member.

6. In a latch, a strike plate having a latch-engaging slot and a buffer retaining member comprising a portion of said plate at right angles thereto turned over to form a pocket. 105

7. In a latch, a frame plate, a spring-urged latching member, a spring-urged pawl having its nose provided with a straight edge to lie flat against said plate when the end of said nose engages the lower 110 edge of said member, the tail of said pawl having a spring-retaining lug thereon of sufficient length to limit the movement of said pawl when striking said plate.

8. In a latch, a sheet metal plate having a front member provided with a rectangular slot, a pivot boss punched from the body of said plate, a top member having a slot punched from its rear edge and a bottom 120 perforated member in line with said latter slot, an actuating rod having a swaged recess therein, a spring on said rod between the displaced metal at said recess and said bottom member, a perforated latching member pivoted on said boss and having a tail 125 engaging said recess, a spring-urged pawl pivoted to the front plate member whose nose engages under said latching member, a spring retaining lug on the tail of said pawl arranged to stop against said plate, 130

and a strike having a V-shaped slot and a buffer arranged to strike the tail of said pawl.

9. In a latch, a strike plate having a V-shaped latch-engaging slot one side of which is substantially parallel to a side of the plate and the other side inclined thereto, a buffer retaining member comprising a portion of said plate at right angles thereto turned over to form a pocket, and a yielding buffer projecting from said pocket, the inclined edge of said slot extending over the

projecting edge of said buffer, whereby, when the latch is slammed shut the upper wider end of said slot will receive the latch 15 irrespective of the degree of compression of said buffer, and the buffer upon expanding will hold the latch against said parallel side of the slot.

In testimony that I claim the foregoing 20 as my invention, I have signed my name hereto.

WILLIAM ROWLEY BRENNAN.
